UNITED STATES PATENT OFFICE.

WILLIAM F. HARRAH AND WALTER H. PARKIN, OF NILES, MICHIGAN, ASSIGNEES TO
NATIONAL-STANDARD COMPANY, OF NILES, MICHIGAN.

DESIGN FOR A LIFTING-JACK STANDARD.

45,837.

Specification for Design.

Patented May 26, 1914.

Application filed April 1, 1914. Serial No. 828,920. Term of patent 7 years.

To all whom it may concern:

Be it known that we, WILLIAM F. HARRAH and WALTER H. PARKIN, citizens of the United States, residing at Niles, in the county of Berrien, State of Michigan, have invented a new, original, and ornamental Design for a Lifting-Jack Standard, of which the following is a specification, reference being had to the accompanying drawing, forming a part thereof.

Figure I is a front view of a lifting jack

standard showing our new design, and Fig. II is a rear perspective view thereof.

We claim:

The ornamental design for a lifting jack standard, as shown.

WILLIAM F. HARRAH.
WALTER H. PARKIN.
